UNITED STATES PATENT OFFICE.

CHARLES L. BROOKS, OF CLEARMONT, WYOMING.

WRENCH.

No. 839,102.

Specification of Letters Patent.

Patented Dec. 25, 1906.

Application filed February 24, 1906. Serial No. 302,793.

To all whom it may concern:

Be it known that I, CHARLES L. BROOKS, a citizen of the United States, residing at Clearmont, in the county of Sheridan and 5 State of Wyoming, have invented certain new and useful Improvements in Wrenches, of which the following is a specification, reference being had therein to the accompanying drawings.

My invention relates to wrenches, and more particularly to that class of combined wrenches embodying a nut-wrench and a pipe-wrench in one tool, the object being to provide a device of the character described 15 that shall be simple and comparatively inexpensive in construction, easy of manipulation and operation, durable and effective, and in which one of the jaws is fixed and the other slidably and adjustably mounted. 20 Other objects and advantages will be manifest from the following description, taken in connection with the accompanying drawings, which are made a part of this specification and in which like numerals designate corresponding parts.

In the drawings, Figure 1 is a perspective view of the complete wrench, and Fig. 2 is a longitudinal section.

1 designates a shank having a fixed jaw 30 member 2 formed integral with one end thereof, said fixed jaw member having a laterally-extending jaw 3 on one side thereof and on the other side a laterally-extending jaw 4, provided with teeth or serrations 5. The 35 other end of the shank 1 is provided with a suitable handle 6, preferably formed in two sections, which fit over the shank and are removably secured in place thereon by means of the screws 7, which pass through openings 40 in the shank. Slidably mounted on the shank is the jaw member 9, which is provided with the laterally-extending jaws 10 and 11, the jaw 11 having a slightly-curved surface, as shown at 12, for the reception of 45 pipes of different diameters. Formed integral with this jaw member 9 is a sliding bar 13, provided with the notches or serrations 14, which are engaged by a pawl 15, which is suitably pivoted on a laterally-projecting 50 lug 16, formed integral with the handle 6 and which passes through an oblong opening 17 in said pawl. The pawl is held in engagement with the notches 14 by means of a coil-spring 18, interposed between the pawl and 55 the handle.

In order that the sliding bar 14 may have

room in which to be operated, the parts of the handle 6 are hollowed out to form an open space, as shown at 19, for the reception of said bar.

The under side of the laterally-projecting lug 4, which is formed integral with the fixed jaw member 2 and which is provided with the notches 5, is suitably inclined, as shown, to engage pipes of different diameters.

In operation the pawl disengages the notches in the sliding bar 14 when the other end is pressed down against the tension of the spring 18, so that the jaw member 9 may be adjusted to fit pipes of different diameters 70 or nuts of different sizes, according to the wish of the operator.

It is thought that the construction and operation of my invention is made clear by the foregoing, taken in connection with the 75 drawings, and further explanation is not deemed necessary.

Having thus described my said invention, what I claim as new, and desire to secure by Letters Patent of the United States, is—

The herein-described combined nut and pipe wrench comprising a shank having at one of its ends a transversely-extending integral head forming two stationary jaws, the inner face of one of the latter being inclined 80 upwardly and outwardly and formed with serrations, a removable handle secured upon the reduced opposite end of said rectangular shank and composed of two half sections each being formed with opposing sockets to 85 receive the end of the shank and with opposing sockets in communication with the first-mentioned sockets, one of said handle-sections being formed with an apertured integral lug projecting laterally from the upper 90 end of said section and having a downwardly and inwardly inclined outer face, screws inserted in transversely-aligning apertures in said handle-sections and said shank for securing said parts together, a sliding head 100 mounted upon said shank and forming sliding jaws to coact with said stationary jaws, the upper face of one of said jaws being curved downwardly and outwardly to coact with the inclined serrated stationary jaw, an integral 105 rack-bar projecting from said sliding head and in slidable contact with one edge of said shank, the lower end of said rack-bar being adapted to slide in the second-mentioned sockets in the handle-sections, a pawl having 110 a pointed end to engage the teeth of said rack-bar and a finger-piece at its opposite end, the

central portion of said pawl being formed with a longitudinal slot to receive the lug on said handle-section and with transverse apertures in alinement with each other and the 5 aperture in said lug, a pivot-pin passed through said alining apertures in said lug and said pawl, and a coil-spring having its opposite ends arranged in seats formed in said

handle-sections and the finger-piece of said pawl, substantially as shown and described. 10

In testimony whereof I hereunto affix my signature in presence of two witnesses.

CHARLES L. BROOKS.
